UNITED STATES PATENT OFFICE.

CLINTON BATEHOLTS, OF HOOSICK FALLS, NEW YORK, ASSIGNOR TO SPECIALTY INSULATION MANUFACTURING COMPANY, INC., OF HOOSICK FALLS, NEW YORK, A CORPORATION OF NEW YORK.

PUSH BUTTON.

Application filed April 13, 1927. Serial No. 183,341.

This invention relates to improvements in push buttons. More particularly it relates to push buttons which are suitable for use as switch elements for making and breaking an electric circuit, by hand or mechanical operation. The invention, for example, may be mounted on the steering post of an automobile for convenient and positive control of a horn, a warning light, a dimmer system, or 10 the like, or may be adapted for wall, desk, clamp or other mounting.

It is an object of the invention to provide a simplified structure whereby such push buttons may be manufactured at small cost, 15 and will be compact and secure in assembly, and attractive in appearance, as well as positive and certain in operation. An important feature, resulting from simplicity and reduction of parts, is that the possibility or break- 20 age or disarrangement of elements is reduced to a minimum.

These objects are attained by employing a single piece body of insulating material which is recessed to receive the head of the 25 button proper, also of insulating material, and which has an axial hole forming a guide for a shank on the button which shank extends into said axial hole and has its end headed or spread in an enlargement of said 30 hole to prevent escape or removal of the button. A single piece spring in the form of a disk or table with integral spring legs is inter- 35 posed between the head of the button and the bottom of the recess in the body, and two terminal contacts, with lead-ins from without, are suitably arranged at the bottom of said recess, under the table, in position to be engaged and connected by the table when the 40 button is depressed. The spring table serves the double function of maintaining the electric circuit open under normal conditions and of completing the circuit when the button is depressed.

Although the invention is illustrated as it 45 may be applied to the type described, wherein the circuit is normally open, the important features involved in the spring are not limited to use in this embodiment.

It is intended that the patent shall cover 50 by suitable expression in the appended claims whatever features of patentable novelty exist in the invention disclosed.

In the drawings:

Figure 1 is an elevation in medial section, of a push button embodying the invention; 55

Figure 2 is a plan with the button removed;

Figure 3 is a perspective of the spring ele- 60 ment per se; and

Figure 4 is a vertical section of a modifica- 65 tion of the device, with lower part of the base 60 broken away.

Referring to the drawing, a single piece body 10, of insulating material, preferably molded of a synthetic composition, has a recess as at 12, from the bottom of which an axial hole 14 extends through the body, the lower portion of which is enlarged as at 15 and has an internal thread to receive the end of a support (not shown) which may be the steering post of an automobile or anything 70 else desired. A hexagonal formation 10^a on the body 10 facilitates attachment to or removal from its support, as a nut. A button 16 loose in the recess 12 and projecting a little from it for convenience of the operator, 75 is held in by a shank 16^a which passes inward through a central hole in a spring table 18 which lies under it within the recess and then further in through the axial hole in the body 10, beyond which, at a suitable distance to 80 allow needed play, it is mushroomed to engage said body in a recess at the further end of this axial hole. The button and table lie together and push each other in and out as a unit. Two contact terminals 20 in the bot- 85 tom of the recess are arranged under the table so as to be engaged and connected electrical- 90 ly thereby when the button is depressed. Conducting wires 22 may enter the recess to these terminals from any direction through the body 10 and may be permanently secured to the terminals. As represented they enter horizontally through holes in the side wall and lie in grooves 12^b in the bottom of the recess. The shank of the button is tubular 95 and is spread at its lower end, after being inserted, to maintain the button slidably in the recess. The upper end may be secured to the button by being spread before the button is molded about it.

The particular construction of spring 18 constitutes an important feature in the attainment of simplicity, compactness and low cost. It requires merely the stamping of a 100

perforated disk from a sheet of phosphor bronze or otherspring metal, with three equally spaced marginal arc-shaped edge portions sheared, and cut free at one end as at 18^a, and 5 the body portion 18^b thereof then displaced out of the plane of the disk to form legs for the remainder of the disk. The free ends constitute feet to rest flatwise on the bottom of recess 12 in body 10. They are located so 10 as not to contact with the terminals 20. To ensure that they do not move into contact one of them may be further bent sharply downward at its end to provide a prong or toe 18^c which engages in a pit 12^a in the recess bottom, thereby to position the spring with its 15 legs out of contact with terminals 20 and to prevent its turning. The wires 22 lying in grooves 12^b in the recess bottom are out of the way of the spring when the latter is depressed by the button; and their permanent attachment to the terminals 20, which are metallic screws or pins set in wells in the bottom of the recess makes the likelihood of a break of connections practically nil after the device as a 20 whole has once been assembled.

In the completed article the wires and contacts are effectively insulated, and yet cannot fail to be connected electrically when the button is depressed; and they are all held securely and permanently in their assembled 30 and operative position by the mere expanding of the bottom end of the tubular shank 14. The thread 15, permits of the button being mounted wherever a designer may wish 35 to use it, with the button 16 in position to be depressed, either by the operator's finger or by any suitable mechanical element.

Although herein illustrated as applied to apparatus in which the depressing of the button 16 closes a circuit, the same principles 40 can be applied for the reverse operation of opening a circuit which is normally closed, or for breaking one circuit and making another as it is possible for switching to occur 45 on either or both sides of the central division containing the terminals.

The recess at either end of the body can be made large enough for containing the table, and the terminals can extend into either recess 50 for the switch contact. The button can be made to push the table toward the contacts, by putting the terminal and disk in the recess wherein the button is; or to push the disk away from the terminals, to break a circuit, 55 by putting terminals and disk normally in spring contact together in the recess remote from the button. In the latter case the disk would be imperforate, would be pushed away from the terminals by the end of the shank of 60 the button, and would be supported by a plug screwed into the threads 15. In either position the spring legs of the table tend to maintain it at all times parallel to the contacts and button.

In Figure 4 the button 24 overhangs the

body 26 with certainty of operating upon being touched in case the driver does not touch exactly in the middle. It is provided on its under side with an annular groove 28 within which the upper portion of body 26 is received when the button is depressed, and the portion surrounded by the groove extends into the button-holding recess 30 with spring and retaining elements identical with those heretofore described. 75

I claim as my invention:

1. A push button comprising an insulating body; electric terminals therein; a single movable contact element for connecting them, having integral spring struts tending to move 80 it so as to disconnect them; and an operating button; said button being slidably mounted in the body and said struts being arranged between said button and said terminals and adapted to hold said element and said button 85 yieldingly away from said terminals.

2. A push button comprising electrical terminals; a connector for them, and spring means normally holding the connector in a certain position with reference to them, combined with a button for dislodging it therefrom; the said spring comprising a metallic disk having marginal portions sheared partially from it and displaced from its plane, and constituting spring legs tending to hold 95 it in the said normal position with respect to the electrical terminals.

3. A push button, comprising an insulating body having a recess with electric terminals on its bottom; a button and means holding it loosely in the recess; said button having an area covering the recess, and having on its under face a conducting material with a plurality of spring legs standing on the bottom of the recess in locations avoiding 100 said terminals and spread apart tending to hold the button parallel to the bottom of the recess, and at a distance where its said conducting material is out of contact with the 105 said terminals.

4. A push button, comprising an insulating body having a recess with a central perforation in its bottom, and with electric terminals on its bottom; a composition button loosely filling the mouth of the recess; means 110 holding the button movably in position, comprising a metallic tube passing loosely through said perforation, having one end firmly secured to the button by being expanded and embedded in the composition thereof, 115 and having its other end loosely secured to the body by being expanded beyond the perforation to a size too large to pass through it; and a plurality of spring struts distributed around the bottom of the recess and tending 120 equally to push the button out, there being means associated with the button to connect the terminals when the button is pressed in. 125

5. A push button, comprising an insulating body having a recess with a central per- 130

foration in its bottom, and with electric terminals on its bottom; and a conducting table standing on said bottom with its top overlying the said terminals and having spring legs which tend to maintain said top of table parallel to said bottom of recess and yielding out of contact with said terminals; and a button overlying said table, loosely filling the mouth of said recess, having a guiding

shank extending into said central perforation, said button having an annular groove in its under face, surrounding the said table and arranged to register with and to receive the top of the wall of said body which surrounds said recess.

Signed at Hoosick Falls, New York, this 7th day of April, 1927.

CLINTON BATEHOLTS.
